UNITED STATES PATENT OFFICE

109,395

DESIGN FOR A DISPLAY CABINET OR SIMILAR ARTICLE

Irving M. Footlik, Chicago, Ill.

Application December 14, 1936, Serial No. 66,514

Term of patent 14 years

To all whom it may concern:

Be it known that I, Irving M. Footlik, a citizen of the United States, residing in Chicago, in the county of Cook and State of Illinois, have invented a new, original, and ornamental Design for a Display Cabinet or Similar Article, of which the following is a specification, reference being had to the accompanying drawing, forming a part thereof.

Fig. 1 is a front and end perspective view, and Fig. 2 is an end elevation of a display cabinet or similar article, showing my new design.

I claim:

The ornamental design for a display cabinet or similar article, substantially as shown.

IRVING M. FOOTLIK.
